LAPPING AND HONING MACHINE

M. Edward Early, Rockford, Ill.

Application October 27, 1944, Serial No. 560,657

4 Claims. (Cl. 51—133)

1

The present invention relates to a machine adapted for lapping or honing articles in quantities and has for its objects generally stated, providing a machine which is simple, easily operated, accurate, can be manufactured at low cost and has high productivity.

The principal objects of the present invention are to provide a rotating head with a number of collets for holding the work, each collet being rotated and oscillated radially, and to provide a motor having abrasion discs secured to the ends of the motor shaft.

An important object of the present invention is to so hold and move the work whereby there is no possibility of inaccuracy or defect as to the finished surface.

To these and other useful ends my invention consists of parts, combinations of parts or their equivalents and mode of operation as hereinafter described and claimed and shown in the accompanying drawings in which:

Fig. 1 is an elevational view of the preferred form of my invention.

Fig. 2 is a top view of the disc carrying unit B.

Fig. 3 is a longitudinal sectional view of the work head.

Fig. 4 is a front view of the work head.

Fig. 5 is a sectional view of the work head taken on line 5—5 of Figure 3.

Fig. 6 is a top view illustrating the mounting of the collet controlling lever.

Fig. 7 is a front view of the device as shown in Figure 6.

Fig. 8 is a horizontal view of the device shown in Figures 6 and 7.

Fig. 9 is a view similar to Figure 7 with the lever removed.

Fig. 10 is a side view of the device as shown in Figure 9.

Fig. 11 illustrates fractionally a modification of member D.

As thus illustrated the base of the machine is designated by reference character A, the disc carrying member is designated in its entirety by reference character B, the work carrying carriage is designated in its entirety by reference character C and the work head is designated in its entirety by reference character D.

Member A may be a frame somewhat similar to a lathe frame and having preferably four carrying legs (not shown). Member A is provided with an extension member 10 which is rigidly attached thereto. Member C is slidably mounted on member 10 having means for manually moving this member. In Figure 1 I illustrate this means by

2

a gear rack 11, a pinion 12 and a hand wheel 13, thus to provide conventional means for moving member D to and from the tool.

Member C is provided with an electric motor 5 (not shown), having a driven shaft 14 to which member D is operatively connected. Member C has a suitable bearing 15 through which shaft 14 extends.

I have shown member C as slidably mounted 10 on member 10 for moving the work to and from the discs on member B. It will be understood that any other suitable means may be supplied for moving member D, for example, the motor and member C may be held stationary and the shaft of member D may be spline connected to the motor shaft or the motor may be slidably mounted on member C or on member 10, the design of the mechanism for moving member D to and from the discs being optional.

Member B is rotatably mounted on member A, the mounting comprising a post 18 having a flange 19 and having rotatably mounted on the post a sleeve 20 with a flange 21. A motor base 23 is turnably mounted on flange 19. The assembly being held together by means of bolts 24, so either members 20 or 23 may be turned on post 18, bolts 24 being preferably positioned so members 20 or 23 may be turned $\frac{1}{4}$ or $\frac{1}{2}$ turn in either direction.

I provide a ring 29 which is held to member 20 preferably by means of four spaced braces 30. I rotatably mount in ring 29 preferably four shafts 31 having discs 32 mounted on their outer ends, each being arranged to carry a sheet of abrasive material or be supplied with an abrasive compound. The ends of the motor shaft are splined and the inner ends of shafts 31 also are splined. I provide a splined collar 33 so these shafts may be operatively connected by moving this member over the spline of a shaft 31 and 35 disconnect the shaft 31 by moving member 33 out of contact with the spline of this shaft.

In some installations, ring 29 and braces 30, including two of the discs and shafts may be dispensed with and two discs 32 mounted directly on the ends of the motor shaft and that by turning the motor $\frac{1}{2}$ turn either disc may be made to contact the work. In either event locking means 45 (not shown) is provided whereby members 21 and 23 may be closely adjusted to a desired position and positively held, the desired position being one in which the face of discs 32 will be held exactly transverse to the shaft which carries member D. For adjusting the work to exactly a vertical position to discs 32, shims (not shown) 50 may be used between members 10 and C.

Referring specifically to member D, an eccentric sleeve 40 is rotatably mounted on shaft 14 having gear teeth 41 and a bearing surface 42, and is held from turning in any suitable manner. For example shafts 48 are secured to member 40 and slidably extend into member C for this purpose. A ring 43 is rotatably mounted on surface 42 and member 43 has rotatably mounted thereon shafts 44 by means of ball bearings 45. I provide pinion teeth 46 on the inner ends of shafts 44 which mesh teeth 41. Thus it will be seen that if member 48 is held from turning and member 43 is rotated, pinions 46 will travel around the axis of teeth 41 as they rotate.

On the forward end of shafts 44 I mount sleeves 59. These sleeves are offset as at 51, the rear end being slidably and rotatably mounted on shaft 44. Offset 51 is, as shown, a distance from the front end of shaft 44. In the spaces between offsets 51 and the ends of the shafts I place springs 49. Members 52 and 53 are keyed to shaft 14, each being provided with slots 54 and 55. Slots 54 are slightly larger than the diameter of the rear of members 50 and slots 55 are slightly larger than the diameter of the front end of members 52. Thus it will be seen that offset 51 will rest against the rear surface of member 53 and shaft 44 will therefore be urged rearwardly, thus to cause collets 60 to engage the work as follows:

Collets or work holding element 60 are screw-threaded into shafts 44 and when the work is placed in the collets which are supplied with outwardly extending flanges 61, springs 49 will urge members 61 into the sleeves, thus to cause the collets to grip the work. Shafts 44 are held in longitudinal working position by offsets 51 and members 61. It will be understood that the design shown in Figure 3 is for purposes of illustration only and that ball bearings 45 will be larger than shown and that all of the parts in member D may be differently designed.

As illustrated ring 43 will be turned by members 52 and 53; however ring 52 may have a pin which extends into member 43 to act as a driver. In this event slots 54 and 55 need not touch the sides of the sleeves.

I provide means for disengaging collets 60 en masse as follows:

An annular disc 70 is slidably mounted on shafts 48 and is normally held adjacent projections 71 on shafts 44 when the collets are engaged. I provide a lever 72 having a shape as shown in Figure 7. This lever at its forward end is pivoted to a shaft 48 as at 73 and the lever is also pivoted to disc 70 as at 74 and 75. Thus it will be seen that by pressing forward on the free end of lever 72 member 73 may be moved forward and contact member 71 so as to disengage the collets, thus releasing the work, so the work can be removed and new pieces inserted in the collets.

After the work is inserted in the collets and before lever 72 is released, member C may be moved forward so plate 32 will hold the work in position until lever 72 is released.

It will be seen that when the collets are loaded with work and plate 32 supplied with an abrasive material and the motors started, the work will be revolved and turned around in circles and moved back and forth across the face of plate 32. The first such operation may be made with plate 32 having a fast cutting abrasive material. After the work is brought into contact for this first operation member B may be turned to another disc on which is applied a finer abrasive material. With the design shown, four different discs pro-

viding four different operations may be used. Generally two only are necessary.

It will be seen that eight different pieces of work may be lapped, polished or rough surfaced at one time and that the operator may without changing the work perform two or more operations on the work; and that because of the oscillating and turning movement of the work and the oppositely turning head and disc, the work will be quickly and efficiently trued, polished or burnished, depending upon the requirements. It will also be seen that if there is a slight difference in the length of the work, by manipulating lever 72 and member C, the faces of the work may be evenly positioned by contact with the disc.

Referring now to Figure 11; this design operates exactly the same in principle as the design shown in Figure 3, the advantage over the other design being that it is simpler and more compact and better adapted for work requiring extreme accuracy. An eccentric sleeve 80 is rotatably mounted on the driven shaft 81 and having gear teeth 82 on its rear end and a bearing surface 83 on its forward end. This sleeve is prevented from turning by means of shafts 48 as in the other design. A ring 84 which corresponds to ring 43 in the other design, is rotatably mounted on bearing surface 83. A collar 85 is secured to shaft 81 having a driver 79. A pin 86 is secured to ring 84 which extends in the path of member 79, thus member 79 will drive ring 84.

I provide a number of collet equipped shafts 87 having gear teeth 88 which mesh teeth 82. Members 87 are rotatably mounted in ring 84 by means of ball bearings 89. A collet shaft 93 is slidably mounted in members 87 as at 91 and 92 so as to form an opening for a spring 93. The forward ends of members 87 and 90 are shaped as shown, members 90 having outwardly extending cone shaped flanges 94. The entire front end of members 90 are split, preferably in four places as at 95 so as to grip the work because of the tension of spring 93. The rear ends of members 90 are provided with projections 71 so member 70, as in Figure 3, may be used to force member 90 forwardly for releasing the work. Opening 96 is suitable to freely receive the work or a stem on the work.

Having thus shown and described my invention, I claim:

1. A lapping machine of the character described, comprising a motor driven disc adapted for use on its face of a lapping compound or an abrasive element, a carrying element having a driven shaft and a work head mounted thereon, means for manually moving the disc and work head toward and from each other, said work head comprising an eccentric gear and bearing member, and being rotatably mounted on said shaft and held from turning by said carrying element, a ring rotatably mounted on said bearing member, a number of spaced shafts rotatably mounted on said ring having pinions secured thereon for engagement with the teeth of said gear, hubs secured to the front end of said driven shaft having radially positioned slots one for each said shafts, work holding collets secured to each said shafts, an offset sleeve slidably mounted on the forward end of said shafts, the forward end of the sleeve being slidably mounted on the collets, a cone shaped projection on the forward end of said collets, springs positioned between the offset of the collets and the front end of said shafts adapted to yieldingly hold said cone shaped surfaces against the forward end of said sleeve, said

collets having openings for the reception of the work and means whereby said springs will cause the collets normally to grip the work, manually operated means at the rear of said work head adapted to contact said shafts and cause the collets to release the work simultaneously.

2. A device of the character described, comprising a head having a protruding driven shaft, an eccentric gear and bearing member rotatably mounted on said shaft, a ring rotatably mounted on said bearing member, a number of spaced collet equipped shafts rotatably mounted on said ring having pinions adapted to mesh said gear, a driving member secured to the end of said driven shaft having radially positioned slots through which the collets extend, means for holding said gear and bearing member whereby when said driving and ring member is turned, the collets will revolve and be turned around said driven shaft and also caused to oscillate radially.

3. A device of the character described, comprising a head having a protruding driven shaft, an eccentric gear and bearing member rotatably mounted on said shaft, a ring rotatably mounted on said bearing member, a number of spaced work holder equipped shafts rotatably mounted on said ring having pinions adapted to mesh said gear, a driving member secured to the end of said

driven shaft operatively connected to said ring, releasable means associated with said work holding means, means adapted to hold said gear and bearing elements from turning, whereby the work will be revolved and also turned around said driving shaft and oscillated radially.

4. A device of the character described comprising; a driver shaft, a hub rotatably mounted on said driver shaft, the forward end of the driver shaft protruding, said hub having a gear on its rear end, a ring rotatably mounted on said hub, a number of circumferentially spaced collet members rotatably mounted in said ring having at their rear ends pinions adapted to mesh said gear, means for holding said hub from turning, a driver secured to the protruding end of said driver shaft having means for turning said ring to thereby cause the collet members to turn around said driver shaft and revolve as they turn, collet shafts slidably mounted in said collet members having springs and means whereby the collet shafts will be moved rearwardly by the springs to cause the collets to engage the work, a longitudinally movable plate in rear of said collet shafts having manually operated means to cause the plate to engage the collet shafts simultaneously to move them forward for disengaging the work.

M. EDWARD EARLY.
